(57) **CLAIM**

The ornamental design for a footwear hook, as shown and described.

DESCRIPTION

FIG. 1 is a top view of a footwear hook.

FIG. 2 is a bottom view of the footwear hook.

FIG. 3 is a front view of the footwear hook.

FIG. 4 is a rear view of the footwear hook.

FIG. 5 is a first side view of the footwear hook.

FIG. 6 is a second side view of the footwear hook; and,

FIG. 7 is a top perspective view of a footwear hook positioned on footwear.
The broken lines depict portions of the structure and environment that forms no part of the claim.

1 Claim, 5 Drawing Sheets
